UNITED STATES PATENT OFFICE.

WILLIAM McBRIDE, OF PORTLAND, MAINE.

SNATCH-BLOCK.

SPECIFICATION forming part of Letters Patent No. 394,499, dated December 11, 1888.

Application filed August 13, 1888. Serial No. 282,622. (No model.)

To all whom it may concern:

Be it known that I, WILLIAM McBRIDE, a subject of the Queen of Great Britain, residing at Portland, in the county of Cumberland and 5 State of Maine, have invented certain new and useful Improvements in Snatch-Blocks; and I do hereby declare the following to be a full, clear, and exact description of the invention, such as will enable others skilled in the art to

10 to which it appertains to make and use the same.

My invention relates to snatch-blocks, although it is capable of being used with other forms of pulley. It is particularly applicable to that class of snatch-blocks wherein the 15 cheeks are of unequal length and the swiveled hook is connected with the longer cheek by a hinged or pivoted connection and to the shorter one by means of a link which is pivoted to the short cheek and hooks over an arm 20 or projection on the swiveled hook provided for that purpose. In these snatch-blocks as they have hitherto been made this link was loosely hinged or pivoted to the short cheek and when the hook was turned, accidentally 25 or otherwise, into a certain position the link was liable to become disconnected, thus causing considerable inconvenience.

The object of my invention is to construct such a snatch-block so that it will be free from 30 liability to become unlatched while in use and will remain always in operative position when once placed therein.

With this end in view I provide the fastening-link, before spoken of, with a suitable 35 spring, which will hold it always in locking position. I also hinge or pivot my swiveled hook to the long cheek of the block, so that in unlatching it may have a longitudinal motion rather than a lateral motion, as heretofore, all as hereinafter shown and claimed.

In the accompanying drawings I illustrate a 40 snatch-block which will embody my invention, although I do not wish to limit myself to the exact construction here shown.

45 In the drawings, Figure 1 is a side elevation of the snatch-block. Fig. 2 is a front elevation of the same. Fig. 3 is an enlarged central vertical section through the upper part of the block, showing certain details.

50 Referring to the drawings, B is the long, and B' the short, cheek. F is the sheave, pivoted

on the pin f. These parts are of ordinary construction and require no further description.

The strap C, which holds or incloses the cheek B, extends in a loop above its upper end, 55 and within this loop is hinged or pivoted the head or block D, which has pivoted to it in the usual manner the swiveled hook A. The free end of the head D is provided with an arm or hook, d, which turns vertically upward, 60 as here shown. The under surface of the hook d is curved, so that as the end of the link strikes it it will be self-latching, as hereinafter shown. The strap C', which supports the cheek B', also forms a loop above the upper end of 65 the cheek B', and within this loop is pivoted the link or latch E, the upper end of which is adapted to engage the hook or arm d. I place under the link E a spring, G, as here shown, composed of rubber, which is confined in a recess formed between the two portions of the strap C', and which press upward against the lower end of the link. This portion of the link is made with a square or flat shoulder, so that the pressure of the rubber forces it to assume 70 an upright position whichever way it may be deflected from that position. It is obvious that any other form of spring may be here used 75 which keeps the link upright or forced toward the head D.

80 The operation of my snatch-block is evident from its construction. When it is desired to insert the rope, the free end of the head D is dropped down until the link E will pass over the end of the hook d. The upper end of the 85 link is then pressed outward, allowing the rope to be inserted. When the link is released, it will spring back to place and place itself in engagement with the hook d. It thus forms an automatically-closing latch which cannot 90 by any ordinary means become disconnected except when it is forced outward for the purpose of changing the rope. By pivoting my head D, as here shown, I am enabled to disengage it by dropping it down longitudinally. 95 This may be done much more rapidly than by the former way, where the hook must be turned to one side. The block as I now construct it is of strong construction, quickly adjusted, and practically incapable of accidentally becoming disengaged.

100 The arm d may be made as a straight stud

instead of a hook, as here shown, as the spring will always keep the link engaged.

I claim—

1. In a snatch-block having a long and short cheek, the combination of a head pivoted to the long cheek, an arm or hook on said head, a link pivoted to said short cheek and adapted to engage said arm, and a spring for holding said link in engagement with said arm, substantially as shown.

2. In a snatch-block having a long and a short cheek, the combination of a head piv-

oted to said long cheek so as to move longitudinally, a hook or arm on the free end of said head, a link pivoted to the said short cheek and adapted to engage said arm, and a spring for keeping said link in engagement with said arm, substantially as shown.

In testimony whereof I affix my signature in presence of two witnesses.

WILLIAM McBRIDE.
